UNITED STATES PATENT OFFICE.

ROBERT C. WEBB, OF BATON ROUGE, LOUISIANA.

SEPTIC TANK.

Application filed May 4, 1926. Serial No. 106,708.

This invention relates to septic tanks and the general object of the invention is to provide a septic tank made up of concrete sections in the general form of pipe sections which may be made in standard sizes and buried in the ground to a desired depth without the aid of skilled labor.

A further object is to provide a septic tank U-shaped in form to provide upwardly extending legs and provide a pipe connecting said legs, this pipe being normally inactive but acting, in case the main pipe of the tank should become clogged, to permit liquids to pass over from the inlet leg to the outlet leg, this pipe further acting to prevent the tank from getting air bound.

My invention is illustrated in the accompanying drawings wherein:—

Figure 1 is a vertical sectional view 20 through a septic tank constructed in accordance with my invention;

Fig. 2 is a top view of the tank.

Referring to these drawings it will be seen that the septic tank is U-shaped in form to provide a longitudinally extending portion A, a vertical inlet leg B and a vertical outlet leg C. The part A consists of a cylindrical pipe section 10 which may be made of concrete, earthen ware, or other suitable material, but is preferably made of concrete, one end of this pipe section 10 having a vertical flat edge face 11 adapted to abut against a corresponding pipe section 10 for the portion B.

Extending vertically downward to form the portion B is the pipe section 12, the lower edge of which is cut on a bevel or miter as at 13 to abut against the angular end of the section 10. The abutting angular ends 40 of the sections 10 and 12 are formed at diametrically opposite points with interlocking lugs and notches 14, the lug 14 engaging in the corresponding notch and preventing any downward movement of the pipe section 12 relative to the pipe section 10. The opposite leg C also consists of the pipe section 12 having its lower end beveled on a 45° angle as at 13, to abut against the end of the corresponding pipe section 10 and it is also provided with interlocking lugs and notches 14.

The vertical leg B is closed at its upper end by a cap 15 and an inlet pipe 16 enters the top of this cap. The leg C adjacent its upper end is provided with an angular outlet pipe 17 which is disposed below the cap

18 and which has a vertical portion extending downward in the leg C and a horizontal portion extending through the side wall of the leg C and discharging into a second tank 60 19. This tank 19 is about 3 or 4' long, is closed at the top by a cap 20, and is provided with an angular outlet pipe 21. This tank 19 may be called the "heavy duty" tank.

An interchange pipe or circulating pipe 65 22 connects the outlet leg C of the septic tank with the inlet leg B. This interchange pipe is preferably made in two sections, the section 22^a being angular in form to extend into the leg B and then downward therein. This 70 interchange pipe is for the purpose of causing the proper circulation of water within the tank that is, to keep the tank from getting air bound and also to keep the water from moving from one side to the other. If 75 at any time the main portion of the septic tank should become stopped up this interchange pipe 22 would permit the water to pass from one side to the other. This will permit the tank to be kept in use for several 80 years without any stoppage. The angular end 22^a of the pipe 22 is designed to be submerged in the water in the septic tank in order to keep any deposits from getting to the other side or leg of the septic tank. This 85 tank is designed to be buried in the ground to any desired depth and the joints are cemented to connect the several sections of the tank. The tanks are then installed and ready for operation.

In operation, the sewage will enter the main tank and remain in this main tank a sufficiently long time to become purified and the supernatant water in this main tank will flow off into the tank 19, will become further purified and will then flow off through the pipe 21 to any suitable distributing point as, for instance, to a ditch, canal, creek or through ordinary drain pipes in the ground.

The tank formed by the section B constitutes a gas chamber where the material is first broken down, while the tank formed by the section C is the fermenting chamber. Some of the material passes on into the tank 19 and some passes back into the portion B. 100 This process goes on until the work is finished. The tank 19 acts as a seal preventing air getting back into the section C and interfering with fermentation, as air otherwise would do. The portion 19 acts to further 105 clear up the water and gives it a second clarification. When proper chemicals are

used in this auxiliary tank 19, such as creosote, carbolic acid and other chemicals, they deodorize the discharged water of any odor that it might have.

5 I claim:—

- 10 1. A septic tank comprising a horizontal tubular body formed in two sections, the sections having abutting ends and the outer ends of said sections having angularly disposed end faces formed with notches and vertical tubular legs, the lower edge of which are beveled to fit against the angular ends of the first named sections and formed with lugs interlocking with said notches, caps for said vertical legs, an inlet pipe entering the upper end of one leg, and an outlet pipe leading from the upper end of the other leg.
- 15 2. A septic tank comprising a horizontal tubular body formed in two sections, the sections having abutting ends and the outer ends of said sections having angularly disposed end faces formed with notches and vertical tubular legs, the lower edges of which are beveled to fit against the angular ends of the first named sections and formed with lugs interlocking with said notches, caps for said vertical legs, an inlet pipe entering the upper end of one leg, and an outlet pipe leading from the upper end of one leg, an outlet pipe leading from the upper end of the other leg, and an interchange pipe connecting said legs adjacent their upper

ends, said pipe within the inlet leg having a downwardly extending portion.

3. A septic tank formed in two tubular sections of uniform diameter throughout their length, each section comprising a vertical leg section and a horizontal leg section, each leg section being cemented to the end 40 of the corresponding horizontal section and each leg section having a cap at its upper end, the ends of the horizontal sections being cemented to each other, an inlet pipe entering one of said legs, an outlet pipe extending from the other leg, and an interchangeable pipe connecting the upper ends of the legs and formed in two sections.

4. A septic tank comprising a horizontal tubular body portion having upwardly extending legs at its ends, the body portion of the legs being of uniform diameter throughout the entire length of the tank, an inlet pipe discharging into one of said legs, an outlet pipe extending from the other leg and having a downwardly turned inner extremity, an interchange pipe connecting the upper ends of the legs, that end of the interchange pipe within the inlet leg of the tank being extended downward, and an auxiliary tank having an outlet, the outlet from the body extending into said auxiliary tank.

In testimony whereof I hereunto affix my signature.

ROBERT C. WEBB.
